United States Patent Office.

JAMES MACKINTIRE, OF NEW YORK, N. Y.

Design No. 4,204, dated July 5, 1870.

DESIGN FOR A BOTTLE.

The Schedule referred to in these Letters Patent and making part of the same.

To all whom it may concern:

Be it known that I, JAMES MACKINTIRE, of New York city, in the county and State of New York, have invented a new and original Design for a Bottle; and I do hereby declare that the following is a full, clear, and exact description thereof, which will enable others skilled in the art to make and use the same, reference being had to the accompanying drawing forming a part of this specification.

The drawing represents a side view of my new bottle.

This invention relates to a new design for the upper parts and necks of glass bottles.

The body A of the bottle is made square, and supports the circular base of the neck, the side of said base being vertical.

From the base A projects a cavetto, b, which constitutes the lower portion of the circular neck, the up-

per part c of the said neck being cylindrical, and smaller in diameter than the top of the cavetto, so that a step, d, is formed between b and c.

A flange, e, projects around the upper end of the bottle.

I do not claim nor confine myself to the shape of the body A of the bottle, which may be cylindrical or prismatic, or of other suitable form; but

I do claim as new and desire to secure by Letters Patent—

The design for the neck of the bottle, consisting of the members a, b, and c, as shown.

JAMES MACKINTIRE.
